UNITED STATES PATENT OFFICE.

ALEXANDER A. OLDHAM, OF GREENSBORO, NORTH CAROLINA.

TRADESMAN'S SIGNAL.

1,101,087.

Specification of Letters Patent.

Patented June 23, 1914.

Application filed July 8, 1913. Serial No. 777,916.

To all whom it may concern:

Be it known that I, ALEXANDER A. OLDHAM, a citizen of the United States, residing at Greensboro, in the county of Guilford and State of North Carolina, have invented new and useful Improvements in Tradesmen's Signals, of which the following is a specification.

The invention relates to indicators, and 10 more particularly to the class of tradesmen's indicators.

The primary object of the invention is the provision of an indicator wherein a pointer and dial can be set by the user so 15 that a tradesman can ascertain at a glance the exact quantity of a commodity or commodities to be delivered to the consumer, the indicator being especially designed for use in notifying dairymen and icemen as 20 to the quantity of butter or sweet milk or cream to be delivered and also the number of pounds of ice to be left or delivered to a house, thereby obviating the necessity of verbal notice to such tradesmen as usual.

25 Another object of the invention is the provision of an indicator of this character which is extremely simple in construction, thoroughly reliable and efficient in its purpose, and inexpensive in manufacture.

30 With these and other objects in view, the invention consists in the construction, combination and arrangement of parts as will be hereinafter fully described, illustrated in the accompanying drawing, and pointed 35 out in the claims hereunto appended.

In the drawings:—Figure 1 is a plan view of an indicator constructed in accordance with the invention. Fig. 2 is a sectional view on the line 2—2 of Fig. 1. Fig. 3 is 40 a sectional view on the line 3—3 of Fig. 1. Fig. 4 is a fragmentary view similar to Fig. 1, with the movable dial partly broken away. Fig. 5 is a rear elevation.

Similar reference characters indicate corresponding parts throughout the several views in the drawings.

Referring to the drawings by numerals, the indicator comprises a card or plate 5 preferably constructed from stiff card board, 50 although it may be made from any other suitable material, for instance, sheet metal, the said card or plate being provided on its front face with a circular dial 6 having at intervals near its periphery indicia 55 such as numerals 7, a series of which ranging from 0 to 50 in multiples of 10, while

the remaining numerals are ranged from 50 to 100 in multiples of 25, while above the said dial 6 and printed or otherwise impressed upon the front face of the card 60 or plate 5 are the words "Ice" and "Milk," the letters of which may be plain or of artistic design to give a neat appearance to the indicator.

Mounted at one side of the dial 8 is a thermometer 8 which is of any ordinary well-known construction to register climatic changes for the convenience of the user of the indicator. Superimposed over the dial 6 is a movable dial 9 forming a rotatable 70 dial which is connected to the card or plate 5 by means of a pivot 10 passed centrally through the said dial 9 and fastened in the card or plate in any suitable manner. The outer face of the disk 9 has printed or otherwise impressed thereon indicia such as numerals as at 11, a series of the numerals ranging from 1 to 10, and the remaining digits being as follows; numerals 12, 16 and the fraction of a unit, namely, $\frac{1}{2}$. These 80 numerals indicate the scale of liquid measure. The numerals on the disk 9 are colored similar to the letters forming the word "Milk," while the numerals on the dial 6 are colored similar to the letters forming 85 the word "Ice," so that the two scales can be readily distinguished from each other and on the reading thereof it can be accurately determined whether the same is indicative of the commodities desired. 90

Rotatably supported upon the pivot 10 are a series of pointers or hands 12, 13 and 14 respectively, which coöperate with the numerals 11 on the dial 9, each hand being colored and its hue distinguishable from 95 the color of the other hands for a purpose presently described.

The disk 9 is provided with a peep opening or hole 15 which is adapted to register with the numerals 7 on the dial 6 so that 100 they may be visible whereby a tradesman can determine the number of pounds of ice to be delivered to a consumer, the dial 9 being set to display or exhibit certain digits indicative of the quantity of ice to be delivered. 105

On the front face of the card or plate 5 near the marginal edges thereof is printed or otherwise impressed a border 16 which gives a neat appearance to the indicator 110 and adds to the ornamental characteristics thereof. Arranged at the rear of the card

or plate 5 and swingingly connected to the pivot 10 are a series of arms 17, 18 and 19 respectively, the free ends of which project beyond one edge of the said card or plate 5, 5 the arm 19 being provided with the letter B, the arm 18 with the letter S, and the arm 17 with the letter C, these letters being colored similarly with respect to the pointers or hands 12, 13 and 14 so that each arm will co- 10 operate with the respective pointer or hand. The arms are movable over a rack bar 20 which is suitably fixed to the rear face of the card or plate 5 and is formed with holding tongues 21 for receiving the respective arms 15 17, 18 and 19 when the same are set for exposing the letters thereon, the letter B being indicative of buttermilk, the letter S being indicative of sweet milk, and the letter C being indicative of cream so that when these 20 arms are set for displaying the letters thereon and the pointers or hands 12, 13 and 14 have been adjusted to aline with the numerals 11 on the disk 9 a tradesman can readily determine the quantity of butter or sweet milk 25 or cream to be delivered to the consumer. The arms 17, 18 and 19 are adapted to swing in an arc whereby the free ends thereof can be moved behind the card or plate 5 and be concealed thereby when it is desired not to 30 display the letters thereon.

From the foregoing it is thought that the construction and manner of operation of the device will be clearly understood, and therefore a more extended explanation has been 35 omitted.

What is claimed is:—

1. An indicator comprising a supporting plate having a circular dial face thereon, a movable disk-like dial superimposed upon the dial face, the said dial face and movable dial being provided with indicia indicative of avoirdupois weight and liquid measurement, respectively, and a pointer traversable over the dial and coöperative with the indicia indicative of liquid measurements, the said movable dial being provided with a peep opening for registry with the indicia on the dial face. 40 45

2. An indicator comprising a supporting plate having a circular dial face thereon, a 50 rotatable disk-like dial mounted upon the plate the dial face thereon, the said dial face and rotatable dial being provided with indicia indicative of avoirdupois weight and liquid measurement, respectively, and a plurality of pointers connected to the pivot of the rotatable dial and traversable over the latter, and a plurality of arms swingingly connected to the pivot of the rotatable dial and arranged at the rear of the plate and 55 having indicia to be exposed, the said rotatable dial being provided with a peep opening for registry with the indicia on the dial face of the said plate. 60

In testimony whereof I affix my signature 65 in presence of two witnesses.

ALEXANDER A. OLDHAM.
